Letters Patent.

The Schedule referred to in these Letters Patent, and making part of the same, containing a description in the words of the said Inventor, showing himself of his improvement in the mode of generating steam in steam engines & other boilers.

No allusion is made to me, as it is known of French inventors of the city of Paris, that have made an important improvement of generating steam in steam engines & other boilers, by which improvement both economy & safety are obtained. That the following is a full and exact description thereof. I make use of such boilers as are generally employed my improvement not being in any way dependent on the particular form thereof but upon the manner in which such boilers are filled or charged with water in combination with other substances, by injection principally into its inside, placing within articles, though porous or solid substances of various kinds so as to fill or nearly to fill its internal cavity with the exception of the spaces between and within such substances - as for example, pieces of globe or irregular lumps of wood of such diameter as may be found convenient say from three inches to one foot or more in diameter, or instead of such pieces, pipes or wooden sticks of small perforation with holes, which should pipe, not to be filled with water along the boiler until it is filled or nearly so - instead of wood, I sometimes employ rocks, coarse or broken pieces of various kinds, taking care however that the substance be such as will not be readily reduced to pulp by boiling in water. In addition, prevent the volatile or other substances so placed as within the water from coming in direct contact therewith, leaving a cavity all around them to be occupied by a steamable mass, such as iron, iron wire, copper, lead, &c &c for many other substances & apparatus in which this is done, I make no claim.

kind of wood and pine together like the leaves of a laurel, this cylinder is capable of holding such a large quantity of water in its interior that the interior of such boiler it should be perforated with holes so as to have such a space divide into two or its outside, extending not out to bear against the sides of the boiler; this will leave a space above mentioned of from one inch to a half to two inches more or less between the wood and the metal. The wooden cylinder is to be filled with blocks of wood or other materials in the way already described. For steam boilers used on land where an immense weight is not objectionable, I sometimes use more solid material than wood such for example, as large field stones, which although they do not possess all the advantages of porous material as yet from their durability will in many cases be preferred.

The increased surface obtained by thus charging the boiler, especially when the softer and more porous woods are employed occasions a great increase in the production of steam, according to my belief that which

arrangement where the actual quantity of water within the boiler is so small as is that above described. For filling with water have such supply pumps, or other means also already known, & add a steam chamber or such other appendages, as may be found convenient.

What I claim as my invention for which such a patent is the placing within boilers of the ordinary construction materials such as I have described, or others calculated to produce a similar result which shall occupy the larger portion of the capacity of such boilers, whilst sufficient space is left between the touching points of the cavities within such substances to contain a quantity of water which may be requisite for the generation of steam.

And witness my signature
John H. Phillips
